UNITED STATES PATENT OFFICE.

FORREST E. GILMORE, OF LOS ANGELES, CALIFORNIA.

COUNTER FLOW STILL.

Application filed April 23, 1925. Serial No. 25,274.

My invention relates to a still for refining mineral oil and its products.

It is an object of this invention to provide a still which may be used as a skimming still for use in a refinery to extract gasoline from crude oil, also as a cracking or converting still, in which case it may be used either singly or connected in series; it may also be used as a still in conjunction with an absorption gasoline plant to distill gasoline from the saturated absorption medium.

With the above and other objects in view which will appear as the description proceeds, my invention consists in the construction and arrangement of parts hereinafter described and claimed.

In the accompanying drawing, which forms a part of this specification,

Figure 1 is a vertical cross section of a still embodying my invention.

Fig. 2 is a horizontal section taken on the line 2—2 of Fig. 1.

Fig. 3 is a horizontal section taken on the line 3—3 of Fig. 1, and

Fig. 4 is a detail view in vertical cross section, showing the arrangement of the heating tubes.

Referring to the drawings, 1 represents the shell of a vertical still closed at the bottom 30 and top and which is shown in Fig. 2 as rectangular in cross section, 2 representing the front and rear sides, and 3 the sides of the shell 1.

In the lower portion of the shell 1 there are arranged in spaced relation a plurality of groups of heating pipes horizontally disposed and having their open ends arranged in the side walls 3 of the shell 1 and designated as 4, 5, 6, 7 and 8, respectively, group 40 4 being near the bottom of the shell 1. Hot gases from a furnace or dutch oven (not shown) communicate by means of a conduit 9 with the lowermost group 4 of the heating pipes. The side walls 3 are provided with flues 10 which conduct the hot gases from one group of heating pipes to the group immediately above, so that the hot gases pass successively through the groups of heating pipes 4, 5, 6, 7 and 8, and from the latter they 50 pass through a smoke stack 11.

Near the top of the shell 1 is a valve-controlled vapor outlet 12 leading to a condenser, not shown. Some distance below the vapor outlet 12 is a temperature regulator

13 comprising a thermocouple, which controls valve 14 in the cold oil inlet pipe 15.

In the upper part of the shell 1, above the groups of heating pipes, there are a series of so-called bubbler trays, horizontally disposed. Each bubbler tray consists of a pan 60 16 having a rim 17, from which the liquid falls onto a circular distributor 18, whence the liquid falls onto a tray 19, from whence the liquid falls through a central downwardly extending pipe 20 which terminates 65 a short distance above the bottom of the pan 16, thus forming a liquid seal.

An inlet 20^a of hot oil enters the still at the point between the third and fourth bubbler trays. In the space above the 70 bubbler trays fine baffling material 21 is disposed for the extraction of mists. The space between the group of heating pipes 4, 5, 6, 7 and 8 is filled with baffling material, shown in the present instance as expanded 75 metal lath 22, although similar material may be substituted therefor. The space between the lowermost group of heating tubes 4 and the bottom of the still constitute an oil collecting chamber 23, from which an outlet 80 pipe 24, controlled by a constant level valve mechanism 25, leads to a heat exchanger, or the like.

As shown in Fig. 4, the heating pipes are preferably arranged in staggered relation 85 and they may be cleaned of any deposits of carbon and the like by removing manhole covers 26 arranged in the front and rear walls of shell 1.

In the operation hot oil is introduced 90 through the inlet 20^a into the still. Some cold oil is also introduced through the cold oil inlet 15 into the still, the amount of the cold oil being regulated by the temperature regulator 13. The cold oil lowers the temperature of the rising vapors and scrubs them in such a way that all the heavy fractions in the vapors which are not desired in the finished product are condensed and returned to the still below. The hot oil passing downwardly from one bubbler tray to another falls over the top group of heating pipes 8 and successively downwardly over the other groups 7, 6, 5 and 4, until it reaches the oil collecting chamber 23, whence 95 it passes out through the outlet 24. As the group of tubes 4 near the bottom of the still are very hot and the groups of tubes 5, 6,

7 and 8 above the first lowermost group are successively of a lower temperature, the oil falling downwardly from one group to another of said heating tubes has its temperature successively raised. As a result there is a slight amount of cracking and each fraction of the oil is given off or evaporated at the lowest temperature at which it will evaporate under the pressure at which the still operates.

As a result, the vapors are partially cracked and a condition of molecular instability is obtained so that there is some rearrangement of the molecules which controls the oil that is treated, and a change in the oil takes place so that the lighter fractions, which are evaporated, pass on to the bubbler trays and out to the condenser, making a satisfactory motor fuel. There is some changing from the paraffin series to the naphthalene series with the result that the product is an anti-knock fuel. Since the gases from the furnace have a counter-flow action with the oil, the fuel economy is very great. The bubbler trays acting as a fractional condenser make it possible to get a finished gasoline or motor fuel without the necessity of re-running it in a steam still.

When the still is used as a cracking or converting still, the temperature at the bottom of the still will be about 800 or 900° F., and there may be some coke formed by this high heat, which may be cleaned off by removing the manhole covers 26, as above stated.

The important part of the still is the counter-flow action, whereby the descending oil passes successively over a set of heating tubes, each succeeding tube being hotter than the one before. Also any condensate in the bubbler trays is returned by gravity to the

hot tubes. The baffling material 21 and 22 increase the surface for the evaporation of the oil.

The still may also be used in an absorption plant, in which case the oil level may be held above the top of the lowest set 4 of the heating tubes.

Thus I have designed a still, simple of construction, and efficient and economical in operation, which may be used as a skimming still, or a cracking or converting still, or a still for distilling off gasoline from absorption medium.

While I have shown the preferred form of construction of the still, it is to be understood by those skilled in the art that various changes in the construction and arrangement of parts may be made without departing from the spirit of the invention, as claimed.

I claim:

A still for use in refining oil, comprising a vertical shell rectangular in cross section, a plurality of sets of heating pipes horizontally disposed in vertical spaced relation in said shell, baffling material disposed between said sets of heating pipes, a hot gas inlet to the lowermost set of heating pipes, means for passing gases successively through the sets of heating pipes disposed above said lower set, a series of bubbler trays disposed in the upper part of said shell, baffling material above said bubbler trays, a vapor exit from the upper part of the shell, a hot oil inlet entering the shell between said bubbler trays, a cold oil inlet above said hot oil inlet, a thermostatic control for the cold oil inlet, and a float controlled oil outlet near the bottom of the shell.

In testimony whereof I have signed my name to this specification.

FORREST E. GILMORE.
